UNITED STATES PATENT OFFICE.

FRANK STAŠEK, OF CLEVELAND, OHIO.

OVEN.

1,136,493.

Specification of Letters Patent. Patented Apr. 20, 1915.

Application filed February 9, 1914. Serial No. 817,449.

To all whom it may concern:

Be it known that I, FRANK STAŠEK, a citizen of the United States, and resident of Cleveland, in the county of Cuyahoga and 5 State of Ohio, have invented certain new and useful Improvements in Ovens, of which I hereby declare the following to be a full, clear, and exact description, such as will enable others skilled in the art to which it 10 appertains to make and use the same.

The objects of the invention are to provide a bake oven in which the amount and distribution of heat can be controlled at the will of the operator, and in which the oven 15 chamber is substantially inclosed by the heating agency, so that the heat will be evenly applied to all sides of the articles treated therein.

The invention further comprises means 20 for separating the chamber into sections and for independently heating the same, this construction permitting of removing the separating means so as to produce a single chamber of the full capacity of the oven.

It also includes a structure composed of 25 detachable flues and connecting devices whereby all parts can be made accessible for cleaning.

It also includes means for forming an air 30 tight ceiling for the oven chamber and further consists in the combination and arrangement of parts and construction of details hereinafter described, shown in the accompanying drawings and specifically 35 pointed out in the claims.

In the accompanying drawings Figure 1 is a central transverse section of the oven; Fig. 2 is a plan view of the oven with the roof removed; Fig. 3 is a horizontal section 40 of the device below the floor of the oven showing the heating flues and fire place; Fig. 4 is a horizontal section of the device just above the oven floor, showing the floor of the oven; Fig. 5 is a longitudinal vertical 45 central section; Fig. 6 is a perspective view of a corner flue connection upon the upper tier of flues; Fig. 7 is a similar view of one of the flues at the side of the oven chamber, showing connections at its ends for other flues; Fig. 8 is a similar view of one 50 of the flues in the upper tier which forms the ceiling of the oven chamber; Fig. 9 is a

similar view of one of the flues forming the lower tier underneath the oven chamber.

In these views 1 is the oven chamber, 2, 3, 4, and 5 are the respective front, side and rear walls thereof.

The oven floor comprises a series of flat topped flues 6, 6 disposed longitudinally of the oven within its walls. Upon these flues 60 rests a metallic floor 7 and upon this a fire brick flooring is laid preferably of loose bricks which can easily be removed when worn out or disintegrated. These flues are spaced from the end walls of the oven chamber and return flues are formed at their extremities by means of the short partitions 65 8, 8 formed preferably of fire brick, which cause a continuous circulation of the products of combustion in the direction of the 70 arrows shown in Fig. 3.

9, 9 are burners for fuel gas or oil or wood or any incandescent fuel can be used and the heated products of combustion pass into the adjacent flues 10, 10, at the center of the 75 oven whence the hot air or gases pass to opposite sides of the oven.

11, 11 are longitudinal flues located at the sides of the oven chamber which communicate at their front ends with the lower tiers 80 of flues through corner blocks 11' and at their rear ends with short transverse flues 12, 12, which are located adjacent to the rear wall of the chamber and which communicate at their inner ends with an upper 85 tier of flues 13, 13, substantially forming the ceiling thereover. This ceiling is made air tight by means of flat stop members M inserted in grooves between the flues 13, 13. These flues are shorter than the chamber 90 and return flues are formed in the spaces thus afforded by means of partitions 14, 14, thus providing a continuous circulation from the center of the chamber outwardly 95 in the direction of the arrows.

Finally the flues at the extreme sides of the oven communicate by means of the hollow corner connections 15, 15, with the transverse flues 16, 16, at the rear of the oven and these in turn communicate with 100 the common chimney 17. In this manner the oven chamber is inclosed on all sides except in the front with the heated flues, and the front is preferably protected by means

of the inner walls 18, 18 which are diagonally placed across the front corners and while forming dead air spaces do not interfere with the working space of the oven chamber.

5 In openings 19 in the outer wall and inner walls incandescent lamps can be placed to illuminate the oven chamber. To separate the oven chamber into two parts a central partition P can be employed which can be lowered by means of the gears 20, 20 and racks 21 and an operating shaft 22. By means of this partition the oven chamber can be divided into two compartments and 10 the compartments can be employed to bake different articles at the same time, and the separate heating systems provide means for providing a different degree of temperature for each compartment, as a slow heat for 15 cakes and confections and a quick heat for bread, etc., at the same time, so that the entire oven can be used at once for baking articles requiring different degrees of temperature if desired. A hinged damper D at 20 the front can be used to close one compartment entirely or the other when it is desired to separate the compartments to use 25 only one of them at a time.

The two heating systems provide means 30 for obtaining an even temperature throughout the oven or when the central partition is used the separate heating systems can provide a given temperature for one and an other temperature for the other. Dampers 35 can be employed in the flues wherever desired.

Since the flues forming the upper tier are long and may sag or become deflected in the middle at high temperatures without 40 support, a central arch A may be thrown over the oven and each flue may be suspended therefrom at its center by means of rods or chains B attached thereto. The top of the oven can be inclosed at T if desired, 45 and a layer of sand can be laid upon the upper tier of flues if desired to retain the heat. A boiler or boilers R, R, shown only in Fig. 1 to furnish hot water for the convenience of the baker can also be placed 50 underneath the arched cover if desired. The flues and spacing members between them can be formed of fire brick, terra cotta or of metal as desired and can readily be put together or taken apart for renewal or cleaning 55 when required. The hollow connecting corner blocks can be formed in separate portions for convenience, and close air tight joints which are integral with the flues are obtained by means of overlapping members 60 as shown in the figures. The flooring plates shown in Figs. 1 and 5 are preferably formed of metal. The chimney can be constructed of any well known material such as metal fire brick or terra cotta as desired. 65 The chimney is provided with lateral open-

ings o, o, into which the extremities of the transverse flues leading thereto project.

Having described the invention what I claim as new and desire to secure by Letters Patent is—

1. In an oven, the combination with the oven chamber, of a tier of longitudinal heat supplying flues underneath, said chamber, said tier formed in two sections, and an oven floor thereover, alternate flues communicating 70 with each other, at their ends in each section to provide a continuous circulation from the center toward each side, longitudinal flues at the sides of the oven chamber communicating with said floor forming flues, 75 a second tier of longitudinal flues in two sections forming upper wall of said chamber, alternate flues communicating with each other at their ends, a transverse flue connecting each section of the upper tier of 80 flues with one of said side flues, a chimney centrally located at the rear of said chamber, and transverse flues connecting said chimney with the respective outer flues of 85 said upper tier, and a heating device for 90 each section of the lower tier of flues.

2. In an oven, a chamber, a lower tier of heat supplying flues underneath said chamber, an upper tier of heat supplying flues above said chamber arranged in two portions, said respective tiers of flues formed in parallel sections longitudinal flues at the sides of the chamber, and transverse flues at the rear of the chamber, said side and transverse flues forming means of communication between said tiers of flues, and encircling three sides of said chamber, a chimney, 95 transverse flues at the rear of said chamber connecting the two portions of the upper tier of flues with said chimney and independent heating means for the sections of 100 said tiers of flues and means for forming dead air spaces at the front corners of said ovens.

3. In an oven, an oven chamber, a lower tier of heat supplying flues arranged in sections underneath said chamber, an upper tier of heat supplying flues arranged in two sections and forming the upper wall of said chamber, a flue forming each side of said chamber, and transverse flues forming the rear wall thereof, said side and transverse flues forming means for communication between the corresponding sections of the lower and upper tiers of flues, a chimney, 110 and flues connecting the sections of the upper tier of flues with said chimney, a movable partition arranged to separate said chamber into compartments corresponding in position to the position of the sections of 115 said tiers of flues, and a separate means of supplying heat to the flues of each compartment.

4. In an oven, in combination, an oven chamber having a front opening, heat con- 120

veying flues inclosing the bottom sides, rear, and top portions of said chamber and arranged in sections, a separate device for supplying a heating medium to each section, 5 a common chimney for said sections, controlling dampers for each section of flues, a removable partition in said chamber separating said chamber into compartments, and a hinged front edge to said partition adapt-

ed to close one side of said front opening in 10 said chamber.

In testimony whereof I hereunto set my hand this 5 day of January, 1913.

FRANK STAŠEK.

In presence of--

RALPH BLUE,
W.M. M. MONROE.
